UNITED STATES PATENT OFFICE.

JOHN E. CHALMAN, OF CHICAGO, ILLINOIS, ASSIGNOR TO UNION SPECIAL MACHINE COMPANY, OF CHICAGO, ILLINOIS, A CORPORATION OF ILLINOIS.

FOLDER FOR SEWING MACHINES.

Application filed November 16, 1914. Serial No. 872,384.

To all whom it may concern:

Be it known that I, JOHN E. CHALMAN, a citizen of the United States, residing at Chicago, in the county of Cook, State of Illinois, have invented certain new and useful Improvements in Folders for Sewing Machines, of which the following is a description, reference being had to the accompanying drawing and to the figures of reference marked thereon.

The invention relates to new and useful improvements in folders for sewing machines and more particularly to a folder which is adapted to form a hem.

15 An object of the invention is to provide a hem folder which is formed of an inner and an outer section and to provide controlling means for separating the sections or withdrawing the inner section from the outer section so as to permit the stitching of circular garments and the overlapping of the stitching at a point where the seam began.

25 A further object of the invention is to provide a folder of the above character with controlling means therefor which automatically returns the inner section of the folder to its normal folding position when released by the operator.

30 A still further object of the invention is to provide a folder which may be readily attached to a cylinder machine and which may be quickly moved away from the stitching mechanism when desired.

35 These and other objects will in part be obvious and will in part be hereinafter more fully disclosed.

In the drawings which show by way of illustration one embodiment of the invention:

40 Figure 1 is a perspective view showing a cylinder machine having my improvements applied thereto;

45 Figure 2 is a plan view of the forward end of the work support, the hem folder and the controlling devices therefor;

Figure 3 is a front view of the same;

Figure 4 is an enlarged longitudinal sectional view on the line 4-4 of Figure 2;

50 Figure 5 is a detail view showing the supporting bracket for the hem folder, the hem folder in normal position, and in dotted lines the folder moved away from the stitching mechanism;

55 Figure 6 is a perspective view showing

the sections of the folder, the needle, and a garment being stitched thereon;

Figure 7 is a perspective view of the folder showing the sections separated;

Figure 8 is a section on the line 8-8 of 60 Figure 4; and

Figure 9 is a detail showing treadle for operating shifting lever.

The invention consists, generally, in providing a hem folder which is made with an 65 inner and an outer section, which sections are shaped and spaced so as to form a hem fold. These sections are mounted so that the inner section may be quickly withdrawn from the outer section at the will of the 70 operator so as to permit the stitching of a hem on a circular garment, such as a trouser leg, or the like, so that the line of stitching may be caused to overlap and align with the stitching at the commencement of 75 the hem. The hem folder is mounted on a bracket which is attached to the work support of the machine, and a lever connected with a treadle or knee shift is provided for separating the sections of the folder. A 80 spring automatically operates to restore the folder to normal folding position.

Referring more in detail to the drawings, I have shown in Figure 1 a cylinder machine consisting of a supporting base 1, above 85 which projects a cylinder work support 2. An overhanging arm 3 is carried by said base and a needle bar 4 reciprocates in said overhanging arm. The needle bar is reciprocated by a needle lever 5. A needle 6 90 is attached to the needle bar and suitable complementary stitch forming mechanism is located in the work support. A presser foot 7 holds the material against the work support.

95 My hem folder 8 is carried by a bracket 9. The bracket 9 is U-shaped so as to extend underneath the work support. The bracket after being positioned on to the work support over the free end thereof, is clamped 100 in position by a clamping screw 10. Adjustable studs 11 and 12 may also be set up against the work support to aid in supporting and positioning the bracket. Pivoted to the bracket is a swinging arm 13 105 which carries a base plate 14. Said base plate 14 is adjustably secured to the arm 13 by suitable screws 14^a and slots 14^b. The bracket is formed with a bearing 15 in which is mounted a pivot stud 16 which is 110

- fixed to the arm by a screw 17. The folder is mounted on the base plate 14. The arm 13 may be swung about the bracket for moving the folder toward and from the stitching mechanism when desired. The arm is held with the folder in normal position adjacent the stitching mechanism by a spring 18 which is fixed to the arm and which bears against a tapered lug 19 carried by the bearing 15. This lug is so shaped as to hold the arm with the folder in the position stated, or also to hold the arm with the folder in the position shown in dotted lines in Figure 5.
15. The base plate 14 extends across the line of feed and supports both sections of the folder. The folder consists of an outer or scroll section 20 and an inner or arbor section 21. The outer section 20 has a shank 22 with slots 23 therein, and suitable screws 24 passing through the slots serve to fixedly attach the outer section of the folder to the base plate 14. By this connection the capacity of the folder can be adjusted to a limited amount to accommodate materials of varying thicknesses. The inner section of the folder is slidably mounted on the base plate 14. Said base plate has a slot 25 extending therethrough. A screw 26 passes through a block 27 and through the slot into the shank 28 of the inner section of the folder. This block is wider than the slot and serves to hold the folder on the base plate. The shank 28 slides in a recess in the upper face of the base plate which permits the inner section of the folder to move back and forth toward and from the outer section of the folder. The movable section 21 of the folder has an extension 21^a formed on the shank thereof which passes underneath the fixed section 20 of the folder. This extension 21^a is adapted to engage a shoulder 21^b, see Figure 4, and limit the inward movement of this movable section of the folder.
45. The outer section of the folder has a vertical concave guiding wall 29 and an overhanging wall 30. The inner face of the overhanging wall merges into the concave face of the vertical wall. The inner section of the folder has a concave vertical wall 31 and an overhanging wall 32 at the upper edge thereof. The underface of this overhanging wall 32 merges into the concave face of the vertical wall. The wall 32 is spaced from the wall 30 so as to permit the fabric F to be inserted between the walls 30 and 32 and the fabric will follow around the concave vertical wall 29 and the concave vertical wall 31, thus forming the hem fold, as clearly shown in Figure 4. Thus the inner section is provided with a guiding wall which faces the wall of the outer section. These walls of the folder are gradually formed from the receiving end toward the delivering end thereof, so as to fold the fabric in a manner

well known in the folder art. The fixed section 20 of the folder has a laterally extending lip 8^a, which extends across the receiving end of the folder when the parts are in normal position for folding the fabric and consequently across the line 8^b between the movable sections. By means of this lip the ravelings are prevented from being caught between the extension 21^a, above referred to, of the movable section and the fixed section. 75 The folder is positioned relative to the stitching mechanism so that the needle 6 passes down through the inner edge of the hem and stitches the same to the body portion of the fabric, as clearly shown in Figure 6 of the drawings. The base 14 being adjustably supported on the arm 13 by screw and slot connections permits the entire folder to be shifted laterally with respect to the needle to vary the margin between the 80 edge of the hem and the line of stitching. 85

The purpose of making the folder in sections is to allow circular garments, such as skirts, trouser legs and the like, to be hemmed and the line of stitching caused to overlap in alinement at the beginning of the stitching of the hem, thus finishing the hem. 90

It will be apparent from Figures 4 and 6 of the drawings that this can not be accomplished without withdrawing the inner section of the folder from the hem in the fabric as the stitched part of the hem would strike against the receiving part of the folder and stop the feed of the garment. The inner section of the folder, however, may be readily withdrawn from the hem, as shown in Figure 6, and when the hemming operation is nearly finished, the folded stitched part of the garment will hold the hem turned in so that the stitching operation 105 may be completed after this section of the folder is withdrawn.

As a means for withdrawing the movable section of the folder, I have provided a rod 33 which is attached to or formed integral with the block 27. This rod slides in a suitable lug 34 carried by the base plate 14. The free end of the rod is provided with a collar 35. A spring 36 encircling the rod bears at one end against the collar and at the other end against the lug 34. This tends to force the rod to the right as viewed in Figure 3 and holds the inner section against the stop 21^b and positioned relative to the outer section for the normal folding operation of the folder. 110 115 120

Pivoted to the supporting base 1 of the machine is a lever 37. This lever is mounted on a pivot bolt 38. The face of the supporting base is recessed and forms a shoulder 39 against which the upper end of the lever is pulled by a spring 40, said spring serving to retain said lever in its normal position. The spring 40 is attached to a lug 41 on the lever and to a lug 42 on the base of the 125 130

machine. This lever has an angle plate 43 attached to its upper end by a clamping screw 44. The angle plate is directly in line with the rod 33, so that when the lever is 5 shifted to the dotted line position shown in Figure 3, the upper end of the lever will engage the rod and move the same so as to carry the movable section of the folder to the dotted line position shown in this figure.

10 This lever 37 may be connected to a foot treadle 37^a or to a knee shift so that it is readily under the control of the operator.

In the operation of my device, the sections 15 of the folder are held in normal folding position by the spring 36, so that there is no strain whatever upon the operator. When the operation of hemming the circular garment is nearly completed, the operator depresses the treadle or operates the knee shift

20 which moves the lever 37, and this, through the rod 33, withdraws the inner section of the folder from the hem fold in the garment and allows the closing or finishing of the hem. Upon releasing the treadle the spring

25 40 automatically returns the lever 37 to its normal position, thereby permitting the spring 36 to automatically return the inner section of the folder to its operative position. The lever may be manipulated in

30 placing the garment in the folder at the beginning of the operation. The essential purpose of the controlling mechanism is to permit the withdrawing of the inner section of the folder so as to finish the hemming 35 operation on the circular garment. It will be understood that this inner section of the folder can be withdrawn without stopping the stitching mechanism.

Inasmuch as there is no connection 40 between the rod 33 and the lever 37, except that the angle plate 43 presses against the end of the rod when shifted, I am able to swing the arm 13 carrying the base plate to the dotted line position shown in Figure 5, 45 so as to move the folder entirely out of operative position and thus give access to the stitching mechanism for any purpose desired. By adjusting the outer section of the folder, the width of the hem may be varied 50 within certain limits. This outer section of the folder has a rearwardly projecting guide 45 which extends alongside of the presser foot 7 and guides the edge of the hem. The presser foot may be provided with a yielding 55 section 46 which, bearing on the upper face of the goods at the single thickness thereof, will tend to guide the inner edge of the hem fold, that is, the edge being stitched.

It is obvious that minor changes in the 60 details of construction may be made without departing from the spirit of the invention as set forth in the appended claims.

Having thus described my invention, what I claim as new and desire to secure by Letters Patent is:

1. The combination with a stitch forming mechanism; of a folder including an outer section and an inner section cooperating therewith to make a circular hem fold, a manually operated member, and 70 means disposed between said manually operated member and the inner section of the folder for withdrawing said inner section from the circular hem fold at will and without stopping the stitch forming mechanism. 75

2. The combination with a stitch forming mechanism; of a folder including an outer section and an inner section cooperating therewith to make a circular hem fold, a treadle controlled lever, and means disposed between the inner section of the folder and said lever whereby said inner section may be withdrawn from the circular hem fold at will without stopping the stitch forming mechanism. 80

3. The combination with a stitch forming mechanism, of a folder including an outer section and an inner section co-operating therewith to make a hem fold, means under 90 the control of the operator for withdrawing said inner section from the hem fold at will without stopping the stitch forming mechanism, and automatic means for returning the inner section to normal folding position when released by the operator. 95

4. The combination with stitch forming mechanism, of a folder for forming a hem fold including an outer section having a concave guiding wall and an inner section having a concave guiding 100 wall facing the wall of the outer section, said inner section having an upper wall projecting into the hem fold, means under the control of the operator for withdrawing said inner section and the upper wall thereof 105 from the hem fold at will, and automatic means for returning the inner section to normal folding position.

5. The combination with stitch forming mechanism, of a folder for forming a hem fold including an outer section having a concave vertical wall and an overhanging wall at the upper edge thereof, and an inner section having a concave vertical wall and an overhanging wall at the upper edge thereof, 110 said overhanging wall on the inner section being located beneath and spaced from the overhanging wall on the outer section, whereby a fabric may be guided between said overhanging walls and folded by the concave 115 walls on said sections, means under the control of the operator for withdrawing the inner section from the hem fold at will, and automatic means for returning the inner section to normal folding position. 120

6. The combination with stitch forming mechanism, of a hem folder including a movable section having a part adapted to extend into the hem fold, means under the control of the operator for withdrawing said part 130

from the hem fold at will without stopping the stitch forming mechanism, said means including a rod connected to the section, a spring for moving the rod so as to hold the section in normal position, and a shiftable lever for engaging the end of the rod and moving the same for withdrawing the movable section from the hem fold.

7. The combination with a work support, 10 a bracket attached to said work support, an arm pivotally connected to said bracket, a base plate carried by said arm, a folder mounted on said base plate, said folder including a fixed section and a movable section, a rod carried by said arm and connected to said movable section for shifting the same relative to the fixed section, a spring engaging said rod for holding the movable section normally in folding position, and 20 a lever mounted independently of said bracket and normally out of engagement with said rod and adapted to be moved into engagement with the rod for shifting the movable section of the folder.

25 8. The combination with a work support, a bracket attached to said work support, an arm pivotally connected to said bracket, a base plate carried by said arm, a folder mounted on said base plate, said folder including a fixed section and a movable section, a rod carried by said arm and connected to said movable section for shifting the same relative to the fixed section, a spring engaging said rod for holding the movable section normally in folding position, a lever adapted to engage said rod for shifting the movable section of the folder, and a spring for normally holding the lever out of contact with the rod whereby said arm may be swung 40 about its pivotal connection with the supporting bracket.

9. In a folding device, a folder comprising relatively fixed and laterally movable sections for forming a hem fold, one of said sections being formed at its receiving end with a guard lip extending across the opening of the folder and merging with the inner face of the other section.

10. The combination with a work support 50 and a stitch forming mechanism; of a folder mounted on the work support to swing forwardly from operative to inoperative position relative to said stitch forming mechanism, said folder including relatively fixed 55 and movable sections, and means under the control of the operator adapted for shifting the movable section of the folder laterally when said folder is in operative position.

60 11. A folding device for forming a hem

fold including an outer fixed section having a concave guiding wall, an inner movable section having a concave guiding wall facing the outer section, said inner section having an upper wall projecting into the hem fold and an extension extending underneath the fixed section for maintaining an unbroken guiding wall in the folding device when the movable section is moved away from the fixed section.

65 12. In a folding device, a folder comprising relatively fixed and movable sections, and means carried by one of the sections for maintaining an unbroken guiding wall in the folder when the movable section is shifted away from the fixed section, one of 70 said sections being formed at its receiving end with a guard lip extending across the opening of the folder and merging with the inner face of the other section.

75 13. The combination with a work support and a stitch forming mechanism, of a folder mounted on said work support to swing toward or away from said stitch forming mechanism, said folder comprising relatively fixed and movable sections, and means under the control of the operator for shifting the movable section at will, said means including a separable connection for permitting the folder to be swung away from said stitch forming mechanism.

80 14. The combination with a stitch forming mechanism; of a folder comprising relatively fixed and movable sections, operating means under the control of the operator for shifting the movable section away from the fixed section without interfering with the operation of the stitch forming mechanism, and automatic means for returning said movable section to normal folding position under 100 release of the operating means by the operator.

85 15. In combination with a sewing machine having stitch forming mechanism and including a needle and a cloth-plate, a hemmer having a relatively fixed scroll section with an edge-guiding member adjacent the line of seam formation, an arbor section interfitting with the scroll section and extending across the line of seam formation in front 110 of the edge-guiding member, and means for shifting said arbor section to one side of the line of seam formation to permit uninterrupted stitching of endless hems.

115 In testimony whereof, I affix my signature in the presence of two witnesses.
